UNITED STATES PATENT OFFICE

STANLEY J. PASK, OF LONG ISLAND CITY, NEW YORK, ASSIGNOR TO AL. H. WOODS,
OF NEW YORK, N. Y.

DESIGN FOR A CASING FOR A CAMERA

Application filed November 25, 1930. Serial No. 37,787. Term of patent 14 years.

To all whom it may concern:

Be it known that I, STANLEY J. PASK, a citizen of the United States of America, and a resident of Long Island City, in the county of Queens and State of New York, have invented a new, original, and ornamental Design for a Casing for a Camera, of which the following is a specification, reference being had to the accompanying drawings, forming a part thereof.

In the drawings, Fig. 1 represents a front view of a casing for a camera embodying my new design,

Fig. 2 is a side view of the same, and
Fig. 3 is a plan view thereof.

I claim:

The ornamental design for a casing for a camera, as shown.

STANLEY J. PASK.
